COMPRESSOR

Filed March 12, 1927

UNITED STATES PATENT OFFICE

JAY G. DE REMER, OF GREENWICH, CONNECTICUT, ASSIGNOR TO SAVAGE-DE REMER CORPORATION, OF NEW YORK, N. Y., A CORPORATION OF NEW YORK

COMPRESSOR

Application filed March 12, 1927. Serial No. 174,899.

The invention relates to compressors, pumps or the like, of the kind which are operated by bodily movement about a central axis, such, for example, as the compressor 5 shown in Patent No. 1,373,175, and more particularly the invention relates to lubricating systems for such types of apparatus, as hereinafter more fully explained.

The accompanying drawing shows a pump 10 of the kind referred to, having the improved lubricating system applied to it, Fig. 1 showing the pump in elevation and partly in section, Fig. 2 an enlarged central section of the main step bearing and oil pump, Fig. 3 15 a bottom plan of said oil pump, cover removed, Fig. 4 a section of the step bearing and oil pump for the compressor proper and Fig. 5 a plan of the latter pump.

Without going into the detail of construction of the compressor shown, which is well known in the art and fully described in said patent, it will suffice to say that the compressor proper, designated generally by reference 20 1, is journalled in an inclined position in a rotating frame 2, which is mounted on a fixed base 3 to rotate about a vertical axis thereon. This frame includes a vertical shaft 4 which is journalled in the base in a top bearing 5, and a step bearing 6. At its upper end, the 25 frame shaft carries a friction wheel 7, by which it is driven, by a pinion on the armature shaft of an electric motor, as indicated. The compressor proper is journalled in the rotating frame in a top bearing 8 and a step 30 bearing 9, and rotates relatively to the frame in these bearings, but does not rotate on its own axis, being held against such rotation by the flexible spiral tubes 10 and 10^a at the upper end of the compressor stem. 35 These tubes hold the compressor somewhat after the manner of a gimbal joint so as to accommodate its bodily movement about the vertical axis, and they also constitute the intake and outlet connections for the compressor, by 40 which the latter is connected, without glands or stuffing boxes, to the rest of the system which is usually stationary.

In the operation of this particular compressor the fluid to be pumped, for example, 45 a refrigerant vapor to be compressed, is ad-

mitted through one of the spirals and passes down through the compressor stem into the body of the compressor wherein it is caught between piston-slugs of mercury or other heavy liquid which form part of a closed 55 mercury circuit actuated by virtue of the rotary motion. The fluid is compressed by the slugs and then discharged out of the mass of mercury through the compressor stem and the other spiral which represents the delivery line, all according to the principle described in said patent. The mere rotation of the frame causes the mercury pistons to act in the manner stated; also, and conversely, the introduction of the fluid in the 60 reverse sense, under pressure, may cause the compressor to act as a motor, so that the apparatus may be regarded either as a pump or a motor so far as the invention is concerned, and accordingly the term compressor 65 body is to be understood in this sense as used herein.

The base or pedestal 3 is hollow and forms an oil reservoir. The oil therein passes through an oil entrance 11 into the chamber 75 of a gear-type oil pump 12, located directly under the step bearing 6 of the main shaft 4. This pump is composed of two meshing spur gears 12, one of which is provided with a key on its upper face mating with a key-slot cut in the reduced lower end of the shaft 4 and both gears are driven by this connection. The pump chamber is constituted by a recess formed in the bottom of the pedestal plate 14 and provided with an attached bottom plate 15. The hub of one of the gears 12 is journalled in this plate and the other in the pedestal plate 14. From the outlet side of the chamber 14 the oil traverses a short channel 16 cut in the bottom plate and extending under the hub of the gear which has the key and passes upwardly through that gear hub and through the bore 4^a of the shaft 4. From the upper part of this shaft the oil is conducted through a duct 17 to the top bearing 8 of the compressor proper. The excess of oil which escapes from the bottom of this bearing falls or is slung by the centrifugal force into the collecting cup 18 formed on the top of the compressor body. 100

The portion which escapes from the top of the bearing 8 reaches the cup 18 through one or more ducts 19 formed between the bearing bush and its seat, as indicated. From the collecting cup 18, the oil passes, by the effect of gravity and centrifugal action, through a duct 20 provided in the compressor body, beneath the heat radiating ribs thereon to an oil conductor 21 by which it is directed into the chamber 22 of the lower bearing 9, normally submerging the latter in oil. The return of the oil back to the reservoir in the pedestal 3 is accomplished by a second gear-type pump located under the step bearing 9 and composed of two meshing gears 23, confined in a pump chamber formed in the attached bottom plate 24. One of these gears is provided with a key 25, mating with a keyway cut in the reduced lower end of the body 1, so as to be held nonrotatively thereto and the hubs of both gears are journaled in the bottom plate 24 so that as the frame rotates, the body 1 being held by its tube connections as above described, the gears 23 will revolve with respect to the chamber. These gears draw the oil from the oil chamber 22 through the channel 26 and deliver it to the channel 27, which latter connects with a tube 28, leading inwardly and upwardly to a point above the top of the pedestal 3 where the oil discharges downwardly into a fixed hopper chamber 29, immediately above the top pedestal bearing 5 and so as to flood the latter. The excess falls through the hole or holes 30 around the bearing back into the oil reservoir. As the frame revolves, both pumps are operated and the oil is thus continuously circulated through all four bearings, each pump delivering to the other. The pump gears 23 are of larger capacity than the gears 12 which enables them to overcome the centrifugal pressure in the oil pipe 28 and safely guard against an excess in bearing 9. The details of the bearings have not been described because the drawings sufficiently illustrate them and because such details are not of consequence to the invention. It will be noted, however, that the top pedestal bearing 5 is provided with an up-standing dam or lip to receive the oil from the upper end of the oil pipe 28, and that the down-turned end of the latter pipe is fitted to a ring 31 around shaft 4 which therefore revolves with the oil pipe. This ring 31 is chambered or flanged so as to overlap the lip on the bearing proper and thereby insures against splashing of oil out of the hopper chamber 29. Similar precaution against spattering or oil slinging is represented by the oil guide 21 leading to the bearing 9 above referred to, which guide is fast to the compressor body and extends well down into the oil chamber 22, overlapping the upstanding lip on the bearing therein and thereby effectively guarding against

escape of oil under high velocity rotation. The collector cup 18, above referred to, is of sufficient depth or height to overlap the lower part of the bearing 8, and thus in like manner prevent oil slinging. This cup is formed of an upward extension of the ribbed cooling jacket which surrounds the compressor body and the oil channel 20 is cut or cast in the inner face of the jacket, thus avoiding exposed oil tubes. The oil tube 28 is concealed in the arm of the rotating frame.

It will be understood from the foregoing that the principle of the invention is not confined to the particular details of design just discussed, nor to the particular style of oil pumps used for feeding the oil back and forth between the body and the frame, but may be incorporated in various different forms within the scope of the invention.

The following is claimed:

1. In apparatus of the kind described a compressor body journaled on a frame journaled on a base, an oil reservoir in the base and two oil pumps associated with and driven by virtue of the relative rotation between frame and base and body and frame respectively, one oil pump delivering to the other assisted by centrifugal action due to the rotation of the parts, and the other delivering back to the reservoir in opposition to said centrifugal action.

2. In apparatus of the kind described, the combination of a base, a frame revolving thereon, a compressor body journaled in the frame, an oil reservoir, an oil pump delivering oil from the reservoir directly to the bearing of said body in the frame, a second oil pump carried by said body and driven by the rotation thereof, delivering oil to one of the bearings in said base.

3. In apparatus of the kind described a compressor body journaled in upper and lower bearings in a revolving frame, an oil pump delivering oil to the upper bearing, a collector cup on the compressor body adapted to catch excess oil from said bearing and means for passing such oil from the cup to the lower bearing.

4. In apparatus of the kind described, a compressor body journaled on a revolving frame, an oil pump driven by the frame and delivering oil to the journal of said body and a second oil pumping means driven by the relative rotation of said body and frame for returning the oil to the first mentioned pump.

5. In apparatus of the kind described, the combination of a base, a frame revolving thereon, a body journaled in the frame, an oil reservoir in the base, an oil pump delivering oil from said reservoir through a part of the frame to a bearing of said body in the frame and means associated with said body for returning oil therefrom to the reservoir.

6. In apparatus of the kind described, the combination of a compressor body journaled

in two bearings on a revolving frame, an oil pump for delivering oil to one of said bearings, an oil passage formed in or on said body, for delivering oil from that bearing to the other bearing, and means associated with said body for returning oil from said bearings back to said oil pump.

7. In apparatus of the kind described, an oiling system comprising an oil circuit including the surfaces to be lubricated, a reservoir, a pump for delivering oil to a part of said circuit, a passage conducting oil from said part by centrifugal action, a second pump receiving such oil and a passage conducting such oil from said second pump back to the reservoir.

8. In an apparatus including a frame and a part rotatable relatively thereto, an oiling system for the bearings of said relatively rotatable part, including an oil reservoir, means for delivering oil therefrom to said bearings, a pump carried by said part and driven thereby, means for delivering the surplus oil from said bearings to the pump and a delivery connection between the pump and said reservoir.

In testimony whereof, I have signed this specification.

JAY G. DE REMER.
